(57) **CLAIM**

The ornamental design for a conference camera as shown and described.

DESCRIPTION

FIG. 1 is a top, front, and right side perspective view of a conference camera showing our new design;

FIG. 2 is a top, front, and left side perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a left side elevation view thereof;

FIG. 8 is a right side elevation view thereof;

FIG. 9 is a back elevation view thereof, shown with an ethernet cable disclosed in broken lines to illustrate an environment;

FIG. 10 is a back elevation view thereof, shown with the conference camera connected to an ethernet cable disclosed in broken lines to illustrate an environment;

FIG. 11 is a bottom, back, and right side perspective view thereof, shown with an ethernet cable disclosed in broken lines to illustrate an environment;

FIG. 12 is a bottom, back, and right side perspective view thereof, shown with the conference camera connected to an ethernet cable disclosed in broken lines to illustrate an environment;

FIG. 13 is a bottom, front, and left side perspective view of the conference camera of FIG. 1;

FIG. 14 is a bottom, front, and left side perspective view thereof, shown with the conference camera attached to a bracket structure disclosed in broken lines to illustrate an environment; and,

FIG. 15 is a top, back, and right side perspective view thereof, shown with the conference camera attached to an ethernet cable and an adapter apparatus disclosed in broken lines to illustrate an environment.

The broken lines showing an ethernet cable, bracket structure, and an adapter apparatus in FIGS. 9, 10, 11, 12, 14, and 15 represent environmental structure and form no part of the claimed design.
